United States Patent

Des. 235,326
Patented June 10, 1975

235,326

VEHICLE TIRE CHAIN APPLICATOR

Serge A. Couttet, Box 561, Georgetown, Colo. 80444

Filed Jan. 2, 1973, Ser. No. 319,976

Term of patent 14 years

Int. Cl. D12—16

U.S. CL. D12—155

FIG. 1

FIG. 2

FIG. 3

FIG. 4

FIG. 5

FIG. 1 is a perspective view of a vehicle tire chain applicator showing my new design;

FIG. 2 is an end elevational view thereof;

FIG. 3 is a top plan view thereof;

FIG. 4 is a side elevational view thereof; and

FIG. 5 is a bottom plan view thereof.

I claim:

The ornamental design for a vehicle tire chain applicator, as shown.
